UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

CENTRIFUGAL FIXTURE.

Application filed May 4, 1925. Serial No. 27,833.

In all the processes of evaporation and distillation, and throughout the arts of fluid purification and rectification, as by separators, it is both assumed and desired that 5 the fluid evolved or treated shall leave the drum or container in a pure state, free from foreign substances, such as heavier liquids and solids. But as a rule the conditions controlling and modifying the operation in 10 some measure defeat this primary expectation and purpose, and, eventuate in producing the escape of impure fluids.

The present invention has relation to centrifugal fixtures, that is, a fixture which does 15 not itself move or rotate, but is so constructed as to induce a strong centrifugal action within the escaping or discharged fluid to the end that the foreign substances and heavier constituents are effectually and certainly removed from outgoing or escaping 20 fluid. The aforesaid foreign substances or heavier constituents are suitably discharged from the devices externally thereof.

The invention has among other objects to 25 perfect and refine the details of devices for carrying out processes of purification, and in the simplest and most reliable manner for the performance of the process. With these and other objects in view, the specific character 30 of the invention will be more readily understood by reference to the accompanying drawings which form a part of this specification, and in which:

Fig. 1 is a longitudinal vertical section of 35 one form of centrifugal fixture embodying this invention.

Fig. 2 is a cross section on the line 2-2 of Fig. 1.

Fig. 3 is a cross section on the line 3-3 of Fig. 1.

Fig. 4 is a longitudinal sectional view of a modified construction.

Fig. 5 is a cross section on the line 5-5 of Fig. 4.

Fig. 6 is a longitudinal sectional view of the device as shown in Fig. 1 provided with an adjustable bottom or follower, and

Fig. 7 is a longitudinal section of a modified construction such as shown in Fig. 4 having also applied thereto an adjustable bottom or follower.

The present invention, which embraces certain structural features which are concerned with features heretofore referred to, embraces tuyères, that is, rotation inducing 55 members, which may be of a number of different constructions but are generally typified by the member 8 herein illustrated. Said member 8, as herein shown, is composed of a top ring 8^a, a plurality of tangentially positioned tuyère blades 8^b, and an imperforate bottom plate or disc 8^c. The inner edges of the blades substantially conform to or meet an imaginary cylinder indicated by the circle 8^d, Fig. 2, and this is true 60

also of the inner periphery of the top ring 8^a. The tuyère blades being tangential to the aforesaid imaginary cylinder, present tangential impact surfaces to the incoming fluid. While other forms and arrangements 65 of tuyère blades than those illustrated by way of example only, may be employed, in any case the blades form long and relatively thin slots or tuyère openings 9 and hence 70 collectively subdivide the fluid into a plurality of thin streams that substantially parallel the axis of the tuyère ring. The vapor or other fluid approaching the fixture impacts the surfaces of the tuyère blades, and is directed by such surfaces into the described relatively thin streams. These 75 streams enter the substantially cylindrical tuyère ring tangentially and, encountering the annular arrangement of blades, combine

to set up a very rapid whirling action within the tuyère ring. On entering the tuyère openings the streams of fluid impact the inner surface of the tuyère blades. These surfaces being preferably tangential in position, conform to the normal angle of incidence 80

of globules of liquid or particles carried by the streams of fluid. These globules instead of being swept away are left or retained upon the inner surfaces of the tuyère blades. The accumulation of such impurities is proportionate to the quantity thereof present in the fluid passing through the fixture, and, as the deposit takes on the general whirling 85

action of the body or fluid within the tuyère ring, that very whirling action insures the 90 retention of the accumulated substances at the periphery of the whirling body, that is, 95 100

on the inner periphery of the tuyère ring. Following the general movement of the whirling body within the tuyère ring, the purified liquid or gas moves axially towards 5 the outlet 10. The upward sweeping action lifts the deposit of impurities to the top of the tuyère ring and into the race-member 14. Arriving there the deposit of impurities is immediately forced outwardly by centrifugal force, and the heavier substances are thus positively and definitely removed from the main stream of fluid and are discharged, at a relatively high velocity from the tangential discharge opening 15.

15 The tuyère ring member 8, the component parts of which have been heretofore described, is mounted in a chamber of cast metal, which in the construction shown in Fig. 1 has flanges 18, 19, at its opposite 20 ends, through which coupling connections are made with the inlet and outlet pipes, 7, 10, which are, respectively, provided with coupling flanges 7^a, 10^a, the flanges of the casing being, if desired, connected with said 25 coupling flanges by bolts 21, whose ends are threaded to receive nuts 22. The race-way 14 is herein shown as formed in the casing 16 and the latter is cast around the ring 8^a of the so-called tuyère member 8. This provides a very convenient and rigid construction, and wherein the tuyère member is 30 reliably and permanently secured in integral manner to the interior of the casing, within which latter said tuyère member is thus suspended with sufficient space surrounding the tuyère blades and the bottom 8^c.

In the modification shown in Figs. 4 and 5 the tuyère member 8 is provided with a bottom 8^c of sufficient thickness to cooperate 40 at its circumferential edge with inwardly projecting, radial lugs 8^d, the latter being formed during the process of casting the casing around the tuyère member 8 so as to engage and support the latter in proper position within said casing. In this construction, also, the walls of the casing are in the casting operation formed with an inwardly 45 projecting annular portion 25 which surrounds and embraces the lower extremity of the tuyère ring so that the latter is held or suspended within the casing 16 by the lugs 8^d and the annular rib or projection 25. In this particular construction the pipes 7, and 50 10, which, respectively, convey the fluid into and discharge it from the casing 16, are threaded into the latter.

In the modification illustrated in Fig. 6, the tuyère member 8 is provided with a bottom 8^c, tuyère blades 8^b, and an upper ring 8^a, which latter is cast within the casing 16, as described in connection with Fig. 1. Under this construction I have shown an 60 adjustable inner wall or bottom member 30, which is swiveled to a screw stem 31, in threaded engagement with a hole in the

bottom 8^c, said stem having preferably a polygonal end 32 for engagement by a wrench or other tool. The adjustable bottom 30 is herein shown as provided with a cone member 35, and is confined to the stem 31 between a head 36 on the latter, and a washer 37. When the stem is turned the bottom may be moved to adjust suitably the area of the openings through the tuyère ring. 75

In the construction illustrated in Fig. 7, the tuyère member 8 is cast with the inwardly projecting lugs 8^d for engagement with the bottom 8^c and with the inwardly projecting cast annulus or rib 25 for engagement with the opposite end portion of the tuyère ring, whereby the latter is cast within and held firmly by the casing 16 in the same manner as heretofore described with reference to Fig. 4. In the construction 80 shown in Fig. 7, I have additionally illustrated an adjustable bottom member 30 which is movable to vary the area of the openings between the tuyère blades by a threaded adjusting screw 31, as illustrated 85 in Fig. 6.

In both the constructions shown in Fig. 6 and Fig. 7, it will be noted that the adjustment of the area of the tuyère openings is effected from the inside of the casing 16 in a 90 construction wherein the tuyère ring is held or sustained within the casing by the expedient of casting the latter about the tuyère ring, so that said ring becomes in effect an integral structure with the casing. 100

Claims:

1. A centrifugal fluid purifying device, comprising, in combination, a casing, a hollow ring member therein and an internally smaller coaxial tuyère ring portion secured 105 within said casing in the process of casting the casing, and adapted to whirlingly direct the fluid into and through said member, said hollow member having a still smaller central outlet axially remote from said tuyère portion and also having a peripheral discharge nozzle.

2. A centrifugal fluid purifying device, comprising, in combination, a circumferential series of tangential tuyère blades, a ring 115 at one end of said blades, and a casing cast about said blades and ring, said ring being embedded in the metal of said casing during the process of casting, and a hollow ring member in said casing of larger diameter 120 than the diameter of said tuyères, and provided with a tangential outlet.

3. A centrifugal fluid purifying device, comprising, in combination, a circumferential series of tangential tuyère blades, a bottom member at one end of said blades, a ring member at the other end thereof, an external enclosing casing for said blades and rings which is cast around said ring and permanently embraces it, and an adjustable plate 130

located within said tuyères and movable by means accessible from within the casing to vary the area of the tuyère openings.

4. A centrifugal fluid purifying device, comprising, in combination, a circular series of tuyère blades, a fixed bottom for said blades, a movable plate adjustable within said tuyère blades, a casing surrounding said

tuyère blades and cast about said blades so as to secure them permanently in position ¹⁰ therein, and a hollow ring member in said casing having a tangential discharge opening.

In testimony whereof I have hereunto set my hand this 30th day of April, A. D. 1925.

CHARLES GILBERT HAWLEY.
